UNITED STATES PATENT OFFICE.

SOLON G. HOWE, OF DETROIT, MICHIGAN.

SHUT-OFF AND PIPE-DRILLING DEVICE.

SPECIFICATION forming part of Letters Patent No. 592,007, dated October 19, 1897.

Application filed March 30, 1897. Serial No. 629,976. (No model.)

To all whom it may concern:

Be it known that I, SOLON G. HOWE, a citizen of the United States, residing at Detroit, county of Wayne, State of Michigan, have 5 invented a certain new and useful Improvement in a Shut-Off and Pipe-Drilling Device; and I declare the following to be a full, clear, and exact description of the invention, such as will enable others skilled in the art to which 10 it appertains to make and use the same, reference being had to the accompanying drawings, which form a part of this specification.

My invention relates to certain new and useful improvements in a shut-off and pipe- 15 drilling device for water-pipes; and it consists of the construction, combination, and arrangement of devices hereinafter described and claimed, and illustrated in the accompanying drawings, in which—

20 Figure 1 is a plan view. Fig. 2 is a view in section on the line 2 2, Fig. 1. Fig. 3 is a view in section on the line 3 3, Fig. 2, showing parts in elevation. Fig. 4 is a view in section on the line 4 4; Fig. 3. Fig. 5 is a side 25 elevation showing the pipe in section. Fig. 6 is a rear end view of the same. Fig. 7 is a detail view of one of the connecting-arms C². Fig. 8 is a view in section on the line 8 8, Fig. 1. Fig. 9 is a view in detail of the plate F. Fig. 10 is a view in detail of the feeding mechanism. Fig. 11 is a view in section on the 30 line 11 11, Fig. 1. Fig. 12 is a detail view of a part of the plate or bar 35, showing the spring to retract the pawl. Fig. 13 is a sectional view of the hinge-valve. Fig. 14 is a view of the sleeve with the wing-gate, showing a modification in the form of the sleeve. Fig. 15 is a detail view, partly in section, showing the packing between the sleeve and pipe. Fig. 16 is a detail view of the reducing-ring E. Fig. 17 is a view of the same in section 40 on the line 17 17, Fig. 16. Fig. 18 is a detail view showing a modification of certain features of my device. Fig. 19 is a detail view 45 showing a preferred construction of the cutter-head. Fig. 20 is a detail view of the arm-cap C⁴. Fig. 21 is a detail view of the arm-cap C³. Fig. 22 is a detail view of the locking device to lock the cap C⁷ and the gate. Fig. 23 is a view in section on the line 23 23, Fig. 22. Fig. 24 is a view in section on the

line 24 24, Fig. 3. Fig. 25 is an inner face view of the head G.

Certain features of my present invention are designed as improvements on an analogous device for which United States Letters Patent were granted to me July 7, 1896, No. 563,488, for pipe tapping and connecting devices.

One object of my invention is to provide 60 economical means of shutting off the flow of water from a water-main to a branch or hydrant connected therewith, portions of the device being designed to be used as a shut-off for hydrant repairs, or to be abandoned after 65 serving as a temporary shut-off, where it is desired to locate a regular dividing-gate at any particular place distant from the pipe-main—as, for example, on a curb-line—to facilitate location when covered with dirt or 70 snow.

Another object of my invention is to combine with my improved shut-off device a novel pipe-drilling device to drill the pipe for making a connection therewith without shutting off the service while the connection is being made.

I carry out the objects of my invention in the following manner:

The numeral 1 denotes a water-pipe. A 80 represents any suitable sleeve engageable on said pipe. The sleeve may be secured to the pipe in any suitable manner, as by wrought-iron bands B passed about the pipe, the sleeve being provided with ears a, through which 85 the ends of the bands pass, nuts a' serving to tighten the bands in engagement with the sleeve.

My invention also contemplates the employment of a supplemental cast-metal yoke 90 B', where wrought-iron bands are liable to be attacked by oxidation or electrolysis. When this cast-metal yoke is required, it is desirable to have it so applied that it may be made a supplemental fastening, to be applied after 95 the sleeve has been secured to the pipe and properly calked, said yoke, preferably, not being relied upon to get a compression of the sleeve and its packing upon the pipe, the yoke being also removable, so as to permit repairs 100 to be readily made to the sleeve connection, if required. The yoke may be secured with

the sleeve in any proper manner. Thus, for example, as shown in the drawings, the sleeve may be formed with additional ears a^2 , and the extremities of the yoke with hooks or shoulders b , wedges B^2 holding the yoke and sleeve firmly together. The sleeve is also formed with hook-lugs a^5 to engage a corresponding lip b' in the lower edge of the outer wedge and prevent a lifting action as the wedge is being driven into place. A suitable packing B^3 , preferably a compressible packing, is located between the sleeve and the pipe, the sleeve being constructed with a suitable recess to receive the packing, as shown.

15 B^4 is a cushion, preferably of wood, extending outward from the packing B^3 , said cushion being used to take the strain, in case any unevenness exists between the radius of the pipe and the radius of the adjacent portion of the sleeve, in the act of compression.

20 B^5 is a lead band surrounding the cushion B^4 and the packing B^3 on the two sides and edges of said packing and cushion, said lead band serving a double purpose, which experience has shown desirable—viz., to secure a greater degree of firmness in the union of the sleeve upon the pipe—and also furnishing an additional water-packing, and one that may be readily calked or hammered up from the 25 outside, when such calking may become necessary, the adjacent portion of the sleeve being so constructed as to permit the ready calking of the lead band, if desired.

30 In making certain connections, as in connecting an eight-inch branch upon an eight-inch pipe, I prefer to employ a supporting-plate B^6 , engaged upon the pipe-main under the wrought-iron bands B , and under the yoke B' , if said yoke is employed, said supporting-plate being constructed with ribs b^3 , embracing the bands B , which, in this case, may be made of round iron bars, as indicated in Fig. 3. This plate, it will be seen, will support the pipe against any liability of breakage, on 35 account of so large a cut being made in the main.

To prevent any liability of breakage of the plate, suitable pockets are made at its extremities between the edges of the plate and the pipe to receive a lead packing, (indicated at b^2 .)

40 Within the outer end of the sleeve I hinge or journal a wing-gate valve C , the hinge-pin or journal being shown at C' , the extremities thereof being supported in the sleeve, as shown. The gate is secured to said hinge-pin by connecting-arms C^2 . My invention contemplates the construction of the hinge-pin C not only to constitute a journal for the 45 gate C , but also to serve, at the same time, as a two-way valve, the hinge-pin being channeled, as indicated at c , and formed with a by-pass having two channels c' and c^2 , communicating with the channel c and diverging so as to be capable of being opened on each 55 side of the gate, when in closed position, when it is desired to equalize the pressure. To this

end the adjacent portion of the sleeve is also formed with passage-ways a^3 and a^4 , with which the channels or ports c' and c^2 in the hinge-pin may be made to register, as shown in Fig. 13, upon a proper movement of the hinge-pin. To provide for this opening and closing of the by-pass through the hinge-pin, as desired, I provide at each end of the hinge-pin arm-caps C^3 and C^4 , said caps encircling the hinge-pin. The cap C^4 is formed with a square orifice, into which a squared portion of the hinge-pin engages, while the cap C^3 is formed with a circular orifice to permit the hinge-pin being passed therethrough into place, a ring C^5 being thereafter located in the circular orifice of said cap, said ring formed with a square orifice to engage a squared portion of the hinge-pin, the ring being locked 75 in position by a key or pin c^3 . These caps are cut away or recessed on their peripheries a desired distance, as shown at c^4 . These caps are made to turn with and by the rotation of the hinge-pin. The arms C^2 are constructed 80 with ribs c^5 , extending across the recesses c^4 of said caps. As so constructed the hinge-pin may obviously be rotated the length of said recesses in said caps before the ribs c^5 of said arms will engage against the end walls 85 of said recesses. This provides for a certain idle movement of the hinge-pin before said caps will engage the ribs of said arms to carry 90 said arms therewith on a further rotation of the hinge-pin to swing the gate. During this 95 idle movement of the hinge-pin its ports c' and c^2 may be brought to register with the passage-ways a^3 and a^4 within the case, so that the by-pass shall be opened and permit 100 an equalization of the pressure. When the arms C^2 have reached the limit of said recesses in said caps, the further movement of the hinge-pin will swing the gate. To permit 105 the ready location of the hinge-pin in place, one side of the sleeve is formed with an orifice of sufficient diameter to admit the pin, as indicated at a^5 , the aperture being closed in 110 the case about the pin by a nut a^6 , said nut being recessed on its outer face to admit of a suitable packing a^7 , and over which is engaged a nut C^6 , upon which is a cap C^7 , engageable by a gate-wrench.

To hold the cap C^7 , and consequently the gate, in place, the cap may be formed with an ear c^{14} , in which is located a pin c^{15} to engage in suitable perforations of the case. The pin c^{15} is grooved to receive a set-screw c^6 to limit the movement of the pin. The pin may be formed with an eye c^7 , engageable by a hooked rod, by which the pin may be lifted 125 to disengage it and permit the rotation of the hinge-pin, the set-screw c^6 limiting the movement of the pin, so that it will not be lifted more than is necessary to allow the gate to swing freely. On the opposite end of the 130 hinge-pin is a packing-nut c^8 and jam-nut c^9 .

To secure the gate C to the connecting-arms C^2 , said arms are constructed at their outer ends each with a square orifice C^8 .

The gate is constructed with lugs C^9 , also formed each with a square orifice c^{10} , a square pin C^{10} uniting the connecting-arms with said lugs, the orifices in said lugs being made sufficiently smaller than said orifices in the arm to allow a slight freedom of action, to compensate for any unevenness that might exist in the gate and the gate-seat c^{11} .

In order to locate the pin C^{10} in place to engage the gate with the arms C^2 , the sleeve is formed with an orifice, as at A' , a cap A^2 closing said orifice.

To center the cutter-head, hereinafter to be described, I form the sleeve A near the extremity toward the pipe with an inwardly-projecting flange A^3 . This flange may either be turned out by a lathe or cut out by the cutter itself in the process of drilling the pipe, said flange serving the purpose of a guide to steady the cutter in cutting through the pipe. The flange is set back a little distance from the pipe, so as to form a chamber A^4 between it and the pipe to receive the chips from the cutting-tool.

The sleeve may be formed with a drip-cock a^8 , located toward its outer end, through which any water may be drained off therefrom outside the closed gate.

It will be seen that the particular construction of my improved gate and hinge-valve forms a very economical and secure device. Their construction also renders it possible to use the same in a spigot-end sleeve, as indicated in Fig. 14, as well as in a bell-end sleeve, inasmuch as my invention contemplates any suitable construction of the sleeve as coming within its scope.

The advantages of the wooden cushion B^4 extending from the packing are obvious, in that such a cushion forms an elastic substance which compensates for any unevenness that may exist in the pipe circumference, thereby preventing an undue strain on the sleeve-casting in drawing the sleeve into place upon the pipe, while it also forms a stop and guide for the lead packing poured around the outer edge of the sleeve at its junction with the pipe-main.

In combination with the sleeve and my improved wing-gate and hinge-valve, I have shown a drilling device provided with a spindle D , carrying a cutter-head D' . Any suitable arrangement of gears may be employed for operating said cutter-head. The drilling device may be engaged upon the sleeve in any suitable manner—as, for instance, by means of a reducing-ring E and a tie-plate F .

G is a head used to secure certain parts of the cutting device upon the tie-plate F . The tie-plate is secured to the reducing-ring in any desired manner, as by screws e . The head G is united to the tie-plate F in any proper manner, as by stud-pins F' . The reducing-ring is provided with set-screws E' to align the reducing-ring centrally with the sleeve. Upon the set-screws are jam-nuts E^2 to lock the screws in position to hold the re-

ducing-ring firmly in place in the operation of the device. The spindle D is sleeved through the head G , as shown. Upon said spindle is located a gear D^2 , which is shown secured in place by means of a ring-plate D^3 , made in halves, said halves being secured to the head G by means of screws d . The plate D^3 is formed with an inwardly-projecting flange d' , fitting into a corresponding groove d^2 in the hub of said gear. By this means the gear is held in place.

H denotes a collar bolted to the gear D^2 to provide for a keyway d^3 , for a key d^4 to operate in, by which the cutter-head is actuated by the turning of said gear. Meshing with the gear D^2 is a pinion J , on the spindle J' of which is located an intermediate gear J^2 , keyed to the spindle J' . The intermediate gear J^2 is actuated by pinions K .

K denotes the journal-bearing in which the journals of the pinion K rotate. The spindle J' is keyed in its bearing by means of a set-screw j to prevent endwise movement thereof. Set-screws k also engage the journals of the gears K to prevent endwise movement.

L denotes cranks by which the pinions K may be operated. Instead, however, of using the pinions K and the intermediate gear J^2 , I may employ a worm-gear, as shown in Fig. 18, in which M denotes a worm meshing with a worm-gear M' , which may be secured upon the shaft J' , the intermediate gear J^2 being dispensed with, the worm-gear M' being substituted therefor. The shaft of the worm M is provided with cranks L' .

To feed the cutter-head, I employ a feed-screw, (indicated by the numeral 20,) one end of which engages a countersunk orifice (indicated at 21) on the adjacent end of the spindle D of the cutter-head.

To automatically actuate the feed-screw, I have shown a pinion 22, meshing with the gear D^2 . The hub of said pinion rotates upon a shaft 23. To hold the pinion in place longitudinally of the shaft and yet permit its revolution thereupon, I provide a friction-collar 24, made in halves, and held upon a grooved ring 25 upon said shaft by means of bolts 26, said collar also having a grooved connection with the hub of the pinion, as indicated at 29. The opposite side of said pinion is engaged with a sleeve 30, having telescopic connection with an additional sleeve 31, suitable clamps 32 being provided to hold the sleeves 30 and 31 in adjusted position. This telescopic connection of the sleeves 30 and 31 will provide for the adjustment of the feed mechanism to different lengths of sleeves.

A . Upon the sleeve 31 is a clamping-arm 33, with which is connected a friction-roll 34. A pressure-bar 35 receives the inner end of the feed-screw, said feed-screw being prevented from turning in said pressure-bar in any suitable manner, as by having the feed-screw constructed with a square head 36, located in a square orifice in said pressure-bar to prevent the turning of the feed-screw.

The pressure-bar is clamped upon the shaft 23, as indicated at 27. The pressure-bar is also clamped upon an additional shaft or bar 18, as indicated at 19, the clamp 19 being 5 preferably a double clamp to allow for any possible spring in the bars 23 and 18. The bar 18 is secured to the head G in any suitable manner, as by a nut 28, a nut 47 engaging the shaft 23 with said head G. Upon the 10 pressure-bar 35 is engaged a sliding bracket 52, said bracket sliding over ways 37 and spring-case 38, and carrying a pawl 39, engageable with a ratchet-wheel 40. With the ratchet-wheel is firmly engaged a nut 41, as 15 by screws 42, the rotation of said nut causing the feeding of the screw 20. Between the ratchet-wheel and the bar 35 is a ball-bearing 43. The nut 41 is provided with operating-handles 44, whereby the nut may be actuated 20 by hand, instead of automatically by the devices hereinbefore described, whenever it is desired. Whenever the friction-roll 34 is rotated, it will evidently contact with the bracket 52 and force it in the opposite direction, causing the pawl 39 to throw the ratchet-wheel 40 a corresponding distance and consequently the nut 41. The throw of the bracket 52 may be governed in any suitable manner. Thus, for example, the pressure-bar 35 may be provided with a series of pin-holes 51, spaced to correspond with the teeth upon the ratchet-wheel. A pin set in any one of said pin-holes will limit the retraction of said bracket, and consequently the throw 30 35 given to the pawl, so that the pawl may give to the ratchet-wheel a throw of a single tooth, or more, as may be desired, upon each rotation of the roll 34. The bracket is retracted by the spring in the spring-case 38. It will 40 be obvious that rotation is given to the nut 41, while the feed-screw 20 is prevented from rotating. In this manner the operation of the feed-screw is made positive, and said screw cannot be operated except by design. 45 After the reducing-ring and tie-plate are adjusted in position upon the end of the sleeve, said ring and tie-plate are securely held in place by tie-rods P, having a jointed engagement with the tie-plate at one end, as 50 indicated at P', to permit said rods to be spread or closed together at their opposite ends to accommodate the different diameters of pipe on which they are applied. The opposite ends of said rods are threaded for a 55 sufficient distance to allow sleeve-nuts P² to slide into engagement with the lugs a. These sleeve-nuts are preferably slightly curved on their outer face to engage a corresponding curve on the lugs a on the sleeve, allowing 60 for variations which the line of the tie-rods might have in the circle of a small or large pipe. Jam-nuts P³ are used to lock the sleeve-nuts in position. The sleeve-nuts are also provided with hook-bolts P⁵, hooking over the 65 bands B to prevent the tie-rods from slipping off from their engagement with the lugs a. Thumb-nuts p upon the outer ends of the

hook-bolts secure the tie-rods to the bands B, preventing the tie-rods from dropping away when the jam-nuts P³ are loosened for any cause.

The reducing-ring is constructed with guide-ribs E² to properly center and aline the cutting mechanism with the ring A³ of the end of the sleeve A. 75

In Fig. 14 a reducing-ring is shown secured upon a spigot end of the sleeve A, while in the remaining figures the reducing-ring is shown secured upon a bell end.

The cutter end is formed, preferably, with a cast head D⁴, provided with a diaphragm D⁵, perforated, as indicated at d⁵, to permit the water to flow therethrough to equalize the pressure while the cut is being made, and also allow the insertion of a bar to drive out the core cut from the pipe after the machine is taken off. The head D⁴ is rigidly engaged upon the spindle D and held from sliding upon the same by means of a headed screw D⁶, the head of the screw lapping over the joint of the spindle with said diaphragm and its hub. 80

To facilitate and cheapen the construction of the cutter-head, I prefer to engage with the head D⁴ a cutter-blade D⁷, rabbeted over the lower end of the head D⁴, as shown, and united thereto by rivets d⁶. This permits the cutter-blade D⁷ being made of a single square bar of steel split and spread in a well-known manner, thereby avoiding a weld, so as to 90 form a blade without a weld. The cutter-blade is preferably made with teeth cut in gangs, a deep cut being made at every third or fourth tooth. By this method I secure the largest possible number of teeth on the cutter-blade, which insures an easy cut and increased durability, avoiding the necessity of sharpening as frequently as would otherwise be required. 100

The head G is provided with a petcock Q, 110 whereby the water may be drawn off from the chamber between the cutter-head and the head G to permit the retraction of the cutter-head.

The spindle D is preferably provided with a handle-bar Q', whereby said spindle may be retracted. It is obvious that the pawl 39 may be thrown out of engagement with the pawl-wheel when it is desired to actuate the nut 41 by hand. Between the reducing-ring E and the end of the sleeve I locate a packing E⁵. Between the reducing-ring and the tie-plate is additional packing, (indicated at F²), while between the tie-plate and the head G, I locate suitable packing, (indicated at G'). 125

While I have shown and described a by-pass through the hinge-pin, yet I would have it definitely understood that certain features of my invention are adapted and calculated to be used with a sleeve and shut-off valve of any suitable construction, and provided with any desired construction of a by-pass to secure the necessary equalization of the pressure, another form of the by-pass being shown 130

in dotted lines in Fig. 3 at a^18 . Thus the cutting and feeding mechanism herein described may be employed with the sleeve and shut-off valve shown in my patent above referred to. 5 So, also, I would have it understood that I do not limit myself in all cases to the employment of the compressible cushion B', as this cushion might in certain cases be omitted, within the scope of my invention, and the 10 lead packing merely surround the compressible packing B⁸. Fig. 1 shows the spindles upon which the cranks L are engageable, the cranks being omitted.

It will be evident where my compressible 15 packing is used with the lead packing on the outside thereof, should the lead be attacked by electrolysis, as is very liable to be the case, under various circumstances, and the lead packing thereby be injured and caused to 20 leak, the inner wood packing receiving the pressure of the water relieves the strain which would otherwise be exerted upon the lead packing, and thereby prevent the lead packing from being blown out from its seat, as is 25 liable to be the result where the inner compressible packing is not employed. My inner compressible packing prevents any leakage under these circumstances, as well as the blowing out of the lead packing, so that when 30 any such injury to the lead packing is discovered it may readily be remedied by hammering the lead packing firmly into place.

What I claim as my invention is—

1. The combination of a sleeve, a shut-off 35 valve to seat within the sleeve, and a hinge-pin carrying said valve, said hinge-pin and sleeve having a by-pass to open therethrough on both sides of the seat of said valve substantially as described.

2. The combination of a sleeve, a shut-off 40 valve to seat within the sleeve, and a hinge-pin journaled in said sleeve carrying said valve, said sleeve and hinge-pin having registrable ports forming a by-pass to open 45 through the sleeve and hinge-pin on both sides of the valve-seat, substantially as described.

3. The combination of a sleeve, a shut-off 50 valve to seat in said sleeve, and a hinge-pin actuating said valve, said sleeve and hinge-pin provided with registrable ports forming a by-pass to open therethrough on both sides 55 of said seat, said hinge-pin having an idle movement to cause said ports to register before actuating said valve, substantially as described.

4. The combination of a sleeve, a shut-off 60 valve to seat within said sleeve, a hinge-pin, and connecting-arms engaging said valve with 65 said hinge-pin, said hinge-pin and sleeve formed with a by-pass to open on both sides of the valve-seat, substantially as described.

5. The combination of a sleeve, a shut-off 65 valve to seat within said sleeve, a hinge-pin provided with arms connecting the valve therewith, and recessed caps engaged upon the hinge-pin, said hinge-pin and sleeve hav-

ing registrable ports to form a by-pass to open on both sides of the valve-seat, and said connecting-arms having a limited movement in 70 the recesses of said caps to cause said passages to register before the valve is actuated, substantially as described.

6. The combination of a sleeve permanently engageable upon a water-pipe, a swinging 75 shut-off valve to seat within said sleeve, a by-pass to open upon both sides of the valve-seat, and means to automatically open and close said by-pass upon the actuation of said shut-off valve, substantially as described. 80

7. The combination of a sleeve permanently engageable upon a water-pipe, a hinge-pin journaled in said sleeve, a swinging shut-off valve connected with said hinge-pin to seat within the sleeve, a by-pass to open upon 85 both sides of the valve-seat, and means actuated by the movement of the hinge-pin to open and close said by-pass substantially as described.

8. The combination of a sleeve permanently 90 engageable upon a water-pipe, a hinge-pin journaled in said sleeve, a swinging shut-off valve carried by said hinge-pin to seat within the sleeve, a by-pass to open upon both sides 95 of the valve-seat, and means actuated by the movement of the hinge-pin to open and close said by-pass, said hinge-pin having a limited movement to open said by-pass before opening the shut-off valve, substantially as described. 100

9. The combination with a sleeve engageable upon a water-pipe, of means to secure the sleeve upon said pipe, said means consisting of wrought-metal bands, and a supplemental cast-metal yoke, said bands and yoke constructed to pass about the pipe and to be engaged with said sleeve, for the purpose described. 105

10. The combination of a pipe, a sleeve engageable upon the pipe, a compressible packing 110 between the sleeve and pipe, means to engage the sleeve upon the pipe and to compress said packing therebetween, and a lead packing on the sides and edges of the compressible packing, substantially as described. 115

11. The combination of a sleeve, means to secure the sleeve upon a pipe, and a supporting-plate held in place between said means and the pipe, substantially as and for the purpose described. 120

12. The combination of a sleeve engageable upon a water-pipe, means to engage the sleeve upon said pipe, an additional supplemental yoke to encircle a water-pipe and engageable with the sleeve to assist in holding the sleeve 125 upon the pipe, and wedges to hold the yoke and sleeve firmly together, substantially as set forth.

13. The combination of a sleeve constructed with hook-lugs a^5 , a yoke engageable therewith to secure the sleeve upon a water-pipe, and wedges to hold the yoke and sleeve firmly together upon the pipe, the outer wedges formed with a lip b' to engage said hook-lugs to pre- 130

vent a lifting action as the wedges are driven into place, substantially as described.

14. The combination of a sleeve, a hinge-pin journaled therein, a swinging shut-off valve, arms connecting said shut-off valve with the hinge-pin, and arm-caps encircling the hinge-pin and rotatable with the hinge-pin, and a by-pass, said caps recessed on their peripheries to permit the hinge-pin being rotated the length of said recesses before actuating the shut-off valve, substantially as set forth.

15. The combination of a sleeve formed with an orifice to admit a hinge-pin, a shut-off valve carried by said hinge-pin, a nut to close said orifice, a packing-nut engageable upon the first-mentioned nut, and a cap engageable on the hinge-pin, substantially as set forth.

16. The combination of a sleeve formed with an orifice to admit a hinge-pin, a nut to close said orifice, a packing-nut engaged therewith, a cap engaged with the hinge-pin, and a locking-pin in connection with said cap, substantially as described.

17. The combination of a sleeve formed with an orifice to admit a hinge-pin, a nut to close said orifice, a packing-nut engaged therewith, a cap engaged with the hinge-pin, and a locking-pin having a limited movement in connection with said cap, substantially as described.

18. The combination of a sleeve, a hinge-pin journaled therein provided with connecting-arms, a shut-off valve or gate connected with said arms, said gate constructed with lugs provided with square orifices, and said connecting-arms constructed with square orifices at their outer ends, and a square pin uniting the connecting-arms with said lugs, substantially as set forth.

19. The combination of a sleeve, a shut-off valve and a reducing-ring engageable upon the outer end of the sleeve, said reducing-ring constructed with guide-ribs, for the purpose described.

20. The combination with a sleeve of a head engaged thereupon, a cutter-spindle sleeved through said head, a gear provided with a hub mounted upon said spindle, and a ring-plate made in halves secured to said head and having a tongue in grooved connection with the hub of said gear, and mechanism to actuate said gear, substantially as and for the purpose described.

21. The combination of a head, a reciprocating cutter-spindle sleeved through said head, a feed-screw bearing against said spindle to feed the spindle to its work, mechanism to advance the feed-screw, and means to hold the feed-screw from turning, said spindle being independently retractable, substantially as described.

22. The combination of a reciprocating cutter-spindle, a support therefor, a feed-screw contacting with the end of said spindle, and

mechanism to automatically feed said screw, said spindle being independently retractable, substantially as set forth.

23. The combination of a reciprocating cutter-spindle, a support therefor, a feed-screw to feed the spindle, automatic mechanism to advance the feed-screw, and means to hold the feed-screw from turning, said spindle being independently retractable, substantially as set forth.

24. The combination of a cutter-spindle, a support therefor, a feed-screw to advance said spindle, a removable pressure-bar to receive one end of the screw, mechanism to advance the feed-screw, and means to prevent the feed-screw from turning within the pressure-bar, substantially as described.

25. The combination of a cutter-spindle, a support therefor, a feed-screw, a removable pressure-bar to receive one end of said screw, a gear mounted upon said spindle, and automatic mechanism actuated by said gear to operate the feed-screw, said feed-screw being non-rotatable, substantially as described.

26. The combination of a reciprocating cutter-spindle, a head through which the spindle is sleeveved, mechanism to drive said spindle, automatic and interchangeable feeding devices to feed the spindle to the work, and a pressure-bar carrying the feeding mechanism, said pressure-bar advanceable toward the cutter-spindle, substantially as described.

27. The combination with a reciprocating cutter-spindle, a support therefor, a pressure-bar, a feed-screw engaged therewith to advance the cutter-spindle, bars 18 and 23 connecting the pressure-bar with said support, sleeves 30 and 31 having a telescopic connection one with the other upon the bar 23, a feed-pinion geared with the cutter-spindle, a friction-roll mounted upon the sleeve 31, a nut to feed the feed-screw, a ratchet-wheel to drive said nut, a sliding bracket, and a pawl carried by said bracket to engage the ratchet-wheel, said friction-roll engageable with said bracket, substantially as and in the manner described.

28. The combination of a reciprocating cutter-spindle a removable pressure-bar, a feed-screw, a ratchet-wheel located upon the feed-screw, and a feed-nut 41 engaged with the ratchet-wheel to reciprocate the feed-screw, substantially as described.

29. The combination of a reciprocating cutter-spindle, a support therefor, bars 18 and 23 connected with said support, a pressure-bar clamped to the bars 18 and 23, and a reciprocating feed-screw carried by the pressure-bar to advance the cutter-spindle, said pressure-bar having a double clamp to engage one of the bars 18 and 23, substantially as described.

30. The combination of a reciprocating cutter-spindle, a head provided with a perforated diaphragm, a headed screw extending longi-

tudinally of the spindle engaging the head to said spindle, and a cutter-blade secured to said head, substantially as set forth.

31. The combination with a reciprocatory cutter-spindle of a head keyed to said spindle and provided with a perforated diaphragm, a headed screw extending longitudinally of the spindle engaging the head to the spindle to hold the head from sliding upon said spindle, and a cutter-head secured to said head, substantially as described.

32. The combination of a sleeve engageable upon a pipe and provided with lugs, a tie-plate secured upon said sleeve, tie-rods having a jointed engagement with the tie-plate, the opposite ends of said rods provided with sleeve-nuts to engage said lugs, and jam-nuts to lock the sleeve-nuts in place, substantially as described.

33. The combination of a sleeve provided with lugs, bands to engage said sleeve upon a pipe, a tie-plate, tie-rods connected to said tie-plate, sleeve-nuts engaged with the opposite extremities of the tie-rods to engage said lugs, jam-nuts to lock the sleeve-nuts, hooked bolts carried by the sleeve-nuts to hook over the bands, and thumb-nuts upon the outer ends of the hooked bolts to secure the tie-rods to the bands, substantially as described.

34. The combination of a sleeve, a hinge-pin, a swinging gate carried by said hinge-pin to seat within the sleeve, a by-pass to open through the sleeve and hinge-pin upon both sides of said seat, and means to hold the gate from closing without design, substantially as described.

35. The combination of a sleeve, a hinge-pin, a swinging gate to seat within the sleeve, connecting-arms to connect the gate with said hinge-pin, a pin to engage said gate with the connecting-arms, said sleeve formed with an opening through which the pin may be engaged in place with the connecting-arms and gate, and means to close said opening, substantially as described.

36. In combination a pipe, a sleeve, means to secure the sleeve upon the pipe, a compressible packing between the pipe and the sleeve, a compressible cushion extending outward from said packing to relieve the strain upon the sleeve in securing the sleeve to the pipe, and a lead packing about said cushion and packing, said cushion serving to form a stop for the lead packing around the sleeve-joint, substantially as described.

37. The combination of a sleeve, a tie-plate, cutting mechanism carried by said plate, and an interchangeable reducing-ring adjustably secured upon said sleeve, substantially as described.

38. The combination of a sleeve, a tie-plate, and tie-rods jointedly engaged with the tie-

plate, said tie-rods adjustably engageable with said sleeve, substantially as described.

39. The combination of a sleeve, a cutter, a support therefor, an independent non-rotatable feed-screw to feed the cutter, a pressure-bar engaging said feed-screw and adjustably connected with said support, whereby the pressure-bar may be accommodated to various lengths of sleeves, substantially as described.

40. The combination of a cutter, a support therefor, means to rotate said cutter, a feed-screw to advance the cutter, a pressure-bar carrying the feed-screw and adjustably connected with said support, an automatic device to actuate the feed-screw and telescoping sleeves carrying the automatic device, substantially as described.

41. The combination of a cutter, an adjustable pressure-bar, an independent non-rotatable feed-screw to advance said cutter housed in said pressure-bar, and means to feed the screw, substantially as described.

42. The combination of a cutter-spindle, a removable pressure-bar, an independent non-rotatable feed-screw rigidly held from turning in said pressure-bar to advance said spindle, and means to reciprocate the feed-screw, substantially as described.

43. The combination of a cutter, driving mechanism to actuate the cutter, an independent non-rotatable feed-screw, a driving-nut to actuate the feed-screw, and adjustable automatic devices to actuate said nut whereby the feeding of the screw may be regulated, substantially as described.

44. The combination of a sleeve, a reducing-ring, packing between said sleeve and ring, a tie-plate secured to the reducing-ring, packing between the tie-plate and ring, a head secured to the tie-plate, packing between the head and tie-plate, and drilling mechanism carried by said head, substantially as set forth.

45. The combination of a pipe, a sleeve engageable upon the pipe, an inner compressible packing between the sleeve and pipe to act as a water packing and also as a cushion to remedy any unevenness between the sleeve and the pipe, means to engage the sleeve upon the pipe, and to compress said packing therebetween, and an outer lead packing on the sides and edges of the compressible packing, the compressible packing receiving the water-pressure and relieving the lead packing therefrom, for the purpose described.

In testimony whereof I sign this specification in the presence of two witnesses.

SOLON G. HOWE.
